(57) **CLAIM**

The ornamental design for a light emitting diode module, as shown and described.

DESCRIPTION

FIG. 1 is a front elevational view of a light emitting diode module in accordance with my new design;

FIG. 2 is a top plan view of the light emitting diode module in accordance with my new design;

FIG. 3 is a bottom plan view of the light emitting diode module in accordance with my new design;

FIG. 4 is a left side elevational view of the light emitting diode module in accordance with my new design; and,

FIG. 5 is a right side elevational view of the light emitting diode module in accordance with my new design.

The opaque line shading illustrates a transparent portion of the light emitting diode module.

The bottom plan view of the light emitting diode module is omitted because the bottom surface of the light emitting diode module is flat and devoid of surface ornamentation.
